CAKE COVERING

Paul Langsam, 605 N. Sweetzer Ave.,
Los Angeles, Calif. 90048

Filed May 15, 1967, Ser. No. 7,136

Term of patent 14 years

(Cl. D59--2)

Fig. 1

Fig. 2

FIG. 1 is a top perspective view of a cake covering showing my new design; and

FIG. 2 is a cross sectional view taken through the center thereof.

The essential features of my design reside in the full line disclosure.

I claim:

The ornamental design for a cake covering, substantially as shown and described.
